WARE FOOT ABRADING MACHINE

Jacob Jordan, New Castle, Pa., assignor to Shenango Pottery Company, New Castle, Pa., a corporation of Pennsylvania

Application February 14, 1951, Serial No. 210,952

10 Claims. (Cl. 51—154)

The present invention relates to a ware foot polishing machine. More particularly, the invention relates to a device for smoothing and removing irregularities which are formed on the foot of ceramic ware during the glazing and firing processes.

When a glazing compound is applied to ware prior to glost firing, any excess compound tends to drain to the lower portions of the ware foot. Subsequent firing of the ware causes hardening of this excess so that irregularities in the foot of the ware result. These irregularities are aggravated when the ware is supported on its foot during either the bisc fire or the glost fire because the support tends to displace the foot of green ware or it tends to displace the glazing compound on the foot of ware being glazed.

The irregularities on the foot of the ware detract from its appearance and tend to scratch and mar surfaces on which the ware is placed. In the manufacture of quality ware it has been the practice to remove these irregularities by laborious hand abrading. This abrading operation has not lent itself readily to performance by automatic or semi-automatic machines since the irregularities are formed on the entire foot surface rather than only on the very bottom of the foot and since the dimensions of ware vary slightly from one piece to the next. Because of the dimensional variation of ceramic ware, even a relatively elaborate and costly contoured abrading wheel does not work, since various dimensions change from one piece of ware to the next. Because of the three-dimensional foot surface to be polished, simple physical translation of an abrading wheel to compensate for variance in piece dimensions cannot be utilized to do the job.

The present invention solves the problem by employing "self-contouring" non-rotating abrading wheels. Each abrading wheel is of such a nature that the foot of a rotating piece of ware will wear its own groove in the wheel. In this manner the foot of each successive piece of ware "tailors" its own conforming groove in its corresponding abrading wheel. Following each piece in its self-tailored groove may be facilitated by resilient ware mounting chucks, as will be more fully explained below.

The primary object of this invention is to provide a machine for abrading and finishing the feet of successive pieces of ware which may vary in dimensions from piece to piece.

Another object of the invention is to provide an abrading surface which will adapt itself to the contour of the surface to be abraded.

A further object of the invention is to provide a novel method of abrading surfaces on successive pieces of non-uniform dimensions.

An additional object of the invention is to provide an abrading surface which will present a fresh, unused portion to each successive piece to be abraded.

Further objects and advantages will become apparent

2

from an examination of the following specifications and claims.

In the drawings:

Figure 1 is a plan view of the invention.

Figure 2 is a section on an enlarged scale taken along line 2—2 in Figure 1.

Figure 3 is a section on the same scale as Figure 2 and taken along line 3—3 of Figure 1.

Figure 4 is a view in section of one of the abrading wheel mounting assemblies on a still larger scale.

Figure 5 is another view of the abrading wheel shown in Figure 4 after the wheel has been advanced from its initial position.

Figure 6 is a view in section on a greatly enlarged scale of a portion of the abrading wheel and an associated ware foot.

Figure 7 is a section on a scale twice that of Figure 4 and showing details of the ratchet advance of the abrading wheel.

In Figures 1 and 3 may be seen the main structural framework of the machine. Suitable foundation members 6 form a support for a bottom plate 7. A top plate 11 is spaced from the bottom plate by side frame members 10. Flush with the top plate is a large turntable 12 which is keyed to and supported by a central shaft 25.

Near the periphery of the turntable 12 a number of spindles 13 are rotatably mounted. Each of these spindles carries a ware chuck 14 at its upper end and spindle pulleys 15 at its lower end. As the turntable 12 turns, all these spindle pulleys except those at the loading station A are driven by long belts 16 which surround all the spindle pulleys. Additional idler pulleys 16A may be mounted on the turntable 12 between each set of spindle pulleys 15 in order to have the path of the belts 16 more nearly approximate a circle. The belts 16 are themselves driven by the pulleys 17. The pulleys 17 are keyed to a shaft 18 to which is also keyed a pulley 19. The pulley 19 constitutes the output end of a conventional Reeves drive powered by the electric motor 20 and the drive ratio of which is varied by adjustment of the handwheel 21.

A second variable speed electric motor 30 is used to turn the turntable 12. Through a belt 31, the motor 30 drives a speed reducer input pulley 32. A spur gear 34 on the speed reducer output shaft meshes with a large gear 35 keyed to the vertical shaft 25.

By means of the above arrangement the turntable 12 may be constantly turned, carrying around with it the spindles 13 and chucks 14. Simultaneously, with the motor 30 running, each spindle 13 and chuck 14 is caused to turn on its own axis at all times during which the associated pulleys 15 are in engagement with the belts 16. Disengagement of each set of pulleys 15 from the belts 16 occurs adjacent the station A, at which time the associated spindle 13 and chuck 14 each ceases to rotate about its own axis.

Associated with each chuck 14 is an abrading wheel mounting assembly. One of these assemblies is shown in detail in Figure 4. An arm 41 is hinged to the turntable 12. A bolt 42 passes through a slot 43 in the arm 41 and is threaded received in an indexing body 44 so that the body 44 is adjustably secured to the arm 41.

A shaft 45 extends through a longitudinal bore in the body 44 and is supported for step-wise rotation therein by suitable sleeves 46. At the end of the body 44 opposite to the hinged connection to the turntable 12 the shaft 45 extends outwardly through a cap member 47. Supported on this end of the shaft is a soft abrading wheel 50, to be more fully described below. The abrading wheel 50 is clamped between collars keyed to the shaft by tightening down on an end nut threaded on the adjacent stud-end of the shaft, as most clearly seen in

Figures 4 and 5. Threads 51 are formed on the opposite end of the shaft 45. These threads are engaged by a nut segment 52 which is removably secured to the body 44 by any suitable means, such as a bolt 55 and plate 56. Extending from the center of the shaft 45 to the left end thereof, as reviewed in Figure 4, is a slot 57. Keyed to this slot is a ratchet wheel 59 which rotates in the portion 60 of the body 44. A spring loaded holding pawl 61 prevents rotation of the ratchet wheel in the counter-clockwise direction as viewed in Figure 7.

Mounted for vertical reciprocation in the portion 44 is a rod 63. A shoulder 64 limits upward movement of this rod. A washer 65 bears against another shoulder 66 on the rod 63 and retains a spring 67 which constantly urges the rod upwardly. Fixed to the rod 63 by means of a bolt 68 and nut member 69 is a resilient pawl 70. With each downward movement of the rod 63 the ratchet wheel 59 is advanced one tooth. Adjacent each abrading wheel mounting assembly on the turntable 12 is a vertical plate 72 having adjustably bolted thereto an abutment 73 which extends over a domed nut 74 threaded to the end of the rod 63.

Under each arm 41 is a lifting rod 75 which passes through the turntable 12 and is supported for reciprocating movement by a suitable sleeve 76 and sleeve inserts 77. A stud 78 on the lifting rod 75 engages a slot in the sleeve 76 to prevent rotation of the lifting rod. A roller 80 is fastened to the lower end of the lifting rod. This roller is adapted to engage a fixed cam 81 as the particular associated abrading wheel mounting assembly approaches the station A. The fixed cam 81 is supported by an assembly bolted to the base plate 7 and generally indicated at 82 in Figure 2. This assembly is also used to support an upper bearing 83 for the vertical shaft 25.

Details of the resilient ware chuck 14 may be seen in Figure 4. The chuck is adapted to receive a piece of ware 85, the rim of which rests upon a suitable soft or resilient ring 86. A plurality of upstanding lugs 87 have a piece of resilient material 88, such as a suitable type of rubber, attached on the inner side thereof. With this arrangement the ware is free to be urged slightly from one side to the other in its resilient mounting.

Each of the abrading wheels 50 is soft or friable enough to enable a ware foot 90 to wear or form its own groove therein. Wheels of this nature may be made from a number of materials. Very satisfactory wheels may comprise silicon carbide granules held together with a suitable binder. The abrading wheels may also alternatively utilize foamed feldspar granules comprising, by weight, approximately 60 percent feldspar, 15 percent flint, 18 percent soda ash and 8 percent marble. These materials are crushed and melted in a furnace. When solidified the batch is chipped out. It is then crushed to size, mixed with liquid sodium silicate and rammed into the proper size mold to form a wheel when dried. The wheel may also be made in the form of a low pressure pneumatic tire supporting an abrasive band. The tire is inflated to grip the band and has enough flexibility to allow it to curve around the contour of the foot.

In operation, the motor 30 is constantly driven to keep the turntable 12 turning. As a given chuck 14 passes station A, its associated pulleys 15 are out of contact with the belts 16, so that the chuck is not turning on its own axis. A piece of ware is placed in inverted position on the chuck by an operator. As the turntable 12 progresses, the pulleys 15 associated with the particular chuck come into contact with the belts 16 and the chuck begins to turn.

At station A the abrading wheel mounting assembly associated with the particular chuck is held in raised position by the push rod 75. As the chuck leaves station A, roller 80 rides down off cam 81 causing the abrading wheel 50 to be lowered into contact with the ware foot 90.

Abrading of the ware foot is continued throughout the

remainder of the cycle of turntable 12 until the particular chuck again approaches station A. At this time the pulleys 15 move out of contact with the belts 16 and the chuck stops turning. The roller 80 contacts the cam 81 and causes the push rod 75 to lift the abrading wheel mounting assembly. As this occurs, the nut 74 on the end of the rod 63 strikes its associated abutment 73 to depress the rod 63 and thereby index the ratchet wheel 59 by one tooth. The shaft 45 is simultaneously rotated through the same angle and, through interaction of the threads 51 and the nut segment 52, is caused to advance slightly to the right as viewed in Figure 4. By means of this indexing arrangement, a fresh portion of the abrading wheel 50 is presented to successive pieces of ware.

After the abrading wheel 50 has been raised and the chuck 14 has stopped turning relative to the turntable 12, the ware is unloaded by an operator. A fresh piece of ware to be abraded is then placed in the chuck by the same operator and the operations described above are repeated.

After a number of pieces have been polished, the used portions of the abrading wheel will form an interrupted spiral path as shown in Figure 5. When the entire surface of the abrading wheel has been used, it is replaced by a fresh one. A used wheel may be redressed to remove the surface notches and may then be re-used. This may be repeated until the wheel is too small in diameter to function properly.

As abrasion of a given ware foot 90 progresses, the foot penetrates the soft polishing wheel so that the wheel surrounds the foot, as may be seen in Figure 6. In ceramic ware, the radius of the ware foot 90 will vary slightly from piece to piece. Also the rim of the ware and the rim of the ware foot are almost always slightly out of round with respect to the vertical axis of the ware and with respect to each other. However, the groove worn by the foot in the wheel 50 together with the resilient mounting 88 enable the abrading wheel to guide the ware, so that the ware is caused to make slight transverse movements in the resilient mounting to compensate for any irregularity of dimension. In this manner, effective automatic abrasion of the ware feet is accomplished despite the dimensional irregularity of successive pieces of ware.

In order to simply remove irregularities on the ware feet by abrasion, rather than to actually cut or reshape the feet, it is preferable to rotate the chucks 14 at a relatively low speed. This low speed also facilitates tracking of each foot 90 and avoids any problem of inertial resistance to high speed transverse movement of ware in the resilient mountings.

While a practical and presently working embodiment of the invention has been herein disclosed, it is to be understood that many alternatives in construction will suggest themselves to those familiar with associated arts. For instance, other drive linkages and other polishing wheel lifting mechanisms may be provided. The chuck lugs 87 may be made adjustable to accommodate various sizes of ware, or, to enable still faster changeover between various sizes of ware, chucks of various sizes may be provided having a standard coupling projection mating with standard centered receiving sockets associated with the spindles 13. Accordingly, the scope of the invention is not to be limited to the specific embodiment disclosed but is to be defined solely by the following claims.

What is claimed is:

1. In an abrader, a turntable, means to rotate said turntable past a fixed station and about a central axis, a plurality of arms hinged to said turntable, a plurality of ware receiving chucks rotatably mounted on said turntable, each of said chucks being associated with one of said arms, means to rotate any given chuck relative to said turntable at all times except when said given chuck is opposite said fixed station, abrading wheel means carried on each of said arms, means to raise each of said arms as it approaches said fixed station and to lower each of said

arms as it leaves said fixed station whereby said abrading wheel means are raised from and lowered to contact with ware carried by said chucks, and means holding each said abrading wheel means against rotation about its own axis throughout the majority of each rotation of said turntable, each said abrading wheel means comprising a friable abrading aggregate penetrable by relatively moving edges of chuck-held ware.

2. In a machine for abrading pieces of ware having at least one upstanding circular ridge varying in distance from the ware axis of revolution by not more than a first dimension, ware chuck means mounted on a base rotatable about an axis of rotation and mounting successive pieces of ware for resilient transverse movement through a second distance relative to said axis of rotation, said second distance being at least equal to said first dimension, means to rotate said chuck means in transverse planes to rotate successively held pieces of ware about their axes of revolution, abrading means penetrable by said ware, means to periodically position said abrading means in apposition to said chuck means and in fixed position relative to said base and to remove said abrading means from said apposition whereby engagement of said abrading means with said ware ridges will be successively effected and terminated.

3. In a machine for abrading pieces of ware having at least one upstanding circular ridge varying in distance from the ware axis of revolution by not more than a first dimension, a plurality of ware chucks to mount successive pieces of ware for resilient transverse movement through a second distance relative to each of said chucks, said second distance being at least equal to said first dimension, first means to successively translate each of said chucks through a cycle, a second means to rotate each of said chucks in transverse planes to rotate successively held pieces of ware about their axes of revolution, a plurality of abrading tools penetrable by said ware, each of said abrading tools being associated with one of said chucks, third means to periodically position each of said abrading tools in apposition to its associated chuck and in fixed position relative to said first means and to remove each abrading tool from said apposition whereby gripping and abrading engagement of each of said abrading tools with ware ridges will be successively effected and terminated.

4. In a machine for abrading pieces of ware having at least one upstanding circular ridge varying in distance from the ware axis of revolution by not more than a first dimension, the combination comprising a chuck rotatable about its longitudinal axis in a mounting, resilient work gripping means on said chuck, said work gripping means being displaceable by gripped work through a second distance at least equal to said first dimension, abrading means adapted to be placed in apposition with the face of said chuck means to bear on work gripped in said chuck, means to hold said abrading means stationary relative to said chuck mounting during the time said chuck is rotated relative to said chuck mounting, said abrading means comprising an abrading aggregate penetrable by ware to be abraded whereby said abrading means is grooved by initial contact with successive work pieces and thereupon shifts successive workpieces transversely in said chuck to compensate for workpiece dimensional variation.

5. In a machine for abrading pieces of ware having at least one upstanding circular ridge varying in radial distances from the ware axis of revolution by not more than a first linear amount, the combination comprising a chuck rotatable in a mounting and adapted to receive successive pieces of work for rotation with said chuck, said chuck comprising resilient gripping means transversely displaceable by gripped work through a second distance at least as great as said first linear amount, abrading means movable into and out of contact with

work gripped in said chuck, said abrading means comprising an abrading aggregate penetrable by ware to be abraded.

6. An abrading machine comprising a table, mounting means to successively rotatably mount on said table work pieces each having an upstanding circular ridge, abrading means mounted on said table and comprising an abrading aggregate penetrable by each of said ridges to establish gripping and abrading contact therewith, means to successively bring said abrading means in contact with ridges on work pieces successively mounted in said mounting means whereby ridge-abrading means gripping contact thereby established will, in response to variation in ridge radius, cause transverse ware-abrading means shifting relative to said table, and resilient means to yieldingly accommodate said shifting.

7. The combination defined in claim 6 together with means to present a fresh portion of said abrading aggregate to successive work pieces.

8. In a device, a turntable, means to rotate said turntable past a fixed station, a plurality of ware receiving chucks rotatably mounted on said turntable, means to rotate any given chuck relative to said turntable at all times except when said given chuck is opposite said fixed station, abrading means associated with each of said chucks, means to lower each of said abrading means into contact with ware held by each associated chuck as said associated chuck leaves said fixed station and to raise each of said abrading means from contact with said ware held by each associated chuck as said associated chuck approaches said fixed station, and means holding each said abrading means against movement relative to said turntable throughout the majority of each rotation of said turntable, said abrading means comprising friable abrading aggregates penetrable by relatively moving edges of chuck-held ware, and means to automatically present a fresh portion of each of said abrading means to successive pieces of ware held in each associated chuck.

9. In an abrader, a turntable, means to rotate said turntable past a fixed station and about a central axis, a plurality of arms hinged to said turntable, a plurality of ware receiving chucks rotatably mounted on said turntable, each of said chucks being associated with one of said arms, means to rotate any given chuck relative to said turntable at all times except when said given chuck is opposite said fixed station, abrading wheel means carried on each of said arms, means to raise each of said arms as it approaches said fixed station and to lower each of said arms as it leaves said fixed station whereby said abrading wheel means are raised from and lowered to contact with ware carried by said chucks, and means holding each said abrading wheel means against rotation about its own axis throughout the majority of each rotation of said turntable, each said abrading wheel means comprising a friable abrading aggregate penetrable by relatively moving edges of chuck-held ware, and said abrading wheel means comprising a cylindrical wheel carried on a shaft threadedly engaged with said arm, ratchet means associated with said shaft whereby when said arm is raised said ratchet means turns said shaft to rotate and advance said cylindrical wheel relative to its associated chuck.

10. In a ware foot finisher a plurality of chucks, first means to successively translate each of said chucks through a cycle, second means to rotate each of said chucks relative to said first means at all times during said cycle except during at least one minor portion of said cycle, third means to bring an abrading tool in contact with work carried in each one of said chucks at all times except during said at least one minor portion, and means holding said abrading tool against movement relative to said first means throughout a majority of said cycle, each said abrading tool comprising an aggregate penetrable by relatively moving edges of chuck-held ware, and indexing means to present a fresh surface of said abrading tool to

said work during successive cycles of said each one of
said chucks.
